Attorney

UNITED STATES PATENT OFFICE

WILLIAM TURNOR LEWIS, OF RACINE, WISCONSIN

THERAPEUTIC LAMP

Application filed May 16, 1929. Serial No. 363,602.

This invention relates to therapeutic lamps.

In therapeutic lamps, particularly those employing an infra-red element, difficulty has been experienced in properly supporting such element, as the element alternately contracts and expands, and as there is a great tendency for the element to sag after extensive use. Further, it is difficult to properly support the element so that its maximum effect is produced without conducting heat to the casing or the support.

In addition to this, the lamps employing infra-red elements usually are so arranged that the central portion of the lamp is obstructed and consequently the ultra-violet producing element frequently used in this type of lamp has to be offset or placed at an inconvenient or less effective position.

This invention is designed to overcome the defects noted above, and objects of the invention are to provide a novel form of therapeutic lamp in which the infra-red element is so supported that it is free to adjust itself to even up inequalities in the tension of the different sections thereof, and is free to slide in its supports to lessen the chances of breaking of the element.

Further objects are to provide a therapeutic lamp in which the infra-red element is supported by spaced members and is held in a spaced relation to the center of the lamp so that the center of the lamp is not obstructed either by the infra-red element itself or by the supports for such element, and to provide the spaced supporting elements with independent adjusting means whereby the elements may be radially adjusted with reference to the lamp to properly position and maintain the infra-red element in its most effective and satisfactory location.

Further objects are to provide a therapeutic lamp in which a reflector or casing is employed in which radially projecting supporting members are provided and equipped with insulating, heat resisting means through which the infra-red element is free to slide to even up inequalities in tension, in which the infra-red element

roughly follows the contour of the casing or reflector, and in which the central portion of the lamp is unobstructed and may be provided with an ultra-violet element.

Further objects are to provide a therapeutic lamp which may be very cheaply manufactured, which is highly serviceable, and which has a long life.

An embodiment of the invention is shown in the accompanying drawing, in which:

Figure 1 is a view looking from the front of the lamp, such view corresponding to a section on a line 1—1 of Figure 2.

Figure 2 is a sectional view on a line 2—2 of Figure 1.

Referring to the drawing, it will be seen that the lamp comprises a casing or reflector indicated generally by the reference character 1. This casing may be circular or of any other convenient shape. It is preferably provided with a rear portion 2 and a front wire mesh protecting screen 3. The casing may be adjustably mounted, for instance, pivotally mounted, within a supporting frame 4, and this frame may be carried by any suitable type of support, for instance, as indicated at 5. If desired, a handle 6 may be provided at the upper portion of the frame to facilitate carrying the lamp about or moving it from point to point in the room.

A plurality of eyelet or hooklike radially extending members 7 project through regularly spaced apertures formed in the casing 1. These members are provided with threaded shanks 8 which are equipped with nuts 9 and 10 located on the inner and outer sides of the casing 1. The eyelet or hooklike portions of the member 7 carry porcelain bushings 11, which may be grooved peripherally to receive the hooklike members, the member 7 being clamped after the porcelain bushings are positioned. These porcelain bushings freely and slidably support the infra-red element 12. This element may be in the form of a coiled resistance unit, such, for instance, as a nichrome composition, adapted to withstand heat without oxidation and without burning. It preferably takes the form of a continuous

helix, as indicated in the drawing. The apertures through the porcelain bushings 11 are preferably rounded at their outer ends, as shown at Figure 1, so as to avoid catching 5 in the convolutions of the infra-red element 12, and to thus permit the utmost freedom of sliding for this infra-red element.

The ends of the infra-red element are connected to the insulated terminals 13 carried 10 by any suitable form of clip or support, as indicated at 14. The terminals are adapted to receive the leads, not shown, by means of which current is supplied the infra-red element.

15 This form of construction readily cooperates with an ultra-violet element, such as indicated at Figure 1. The ultra-violet element may take any desired form, for instance, as shown in the drawing, the ultra-violet rays may be produced by means of an arc structure between a pair of carbons or other electrodes 15, which are held by the adjustable clamps 16. These clamps may be guided by the supporting bar 17 or guide, 20 and are moved towards or from each other by the reversely threaded rod or screw 18, such screw extending through the casing and being provided with a knurled operating handle or disc 19. If desired, a small pan-like or cuplike member 20 may be carried centrally of the guide 17 and may be located below the adjacent ends of the carbons, to catch any falling material during the operation of the arc. The carbons may be supplied with current through flexible leads, 30 not shown, or by any other desired means.

It is to be noted particularly that the infra-red element is held in spaced relation to the central portion of the lamp and 40 consequently the ultra-violet element occupies a free and unobstructed space, so that the infra-red rays and the ultra-violet rays may pass freely from the lamp, and the most effective or efficient condition is thereby obtained.

It is intended that either element be operated independently of the other, or that both be operated simultaneously.

It is to be noted also that the infra-red 50 element is held at a plurality of spaced points and is slidably carried. As the element heats up, it slightly expands, and this expansion may be unequal. The manner of supporting the element permits a free adjustment to take place so that the tension in the different sections of the element can be evened up automatically. In addition to these advantages, it is apparent that the exact positioning desired may be readily obtained by adjusting the radially positioned 55 supporting members inwardly or outwardly, as desired.

Further it is to be noted, that there is 60 practically no direct conduction of heat from the infra-red element to the casing.

The construction is extremely simple and may be most easily produced at a very small cost.

It has been found in actual service, that the lamp operates in the manner described in detail above, that it has a long life, and that it is highly serviceable in practice.

Although the invention has been described in considerable detail, it is intended that this description be interpreted as illustrative, as the invention may be variously embodied and is, as stated, to be interpreted as claimed.

I claim:

1. A therapeutic lamp comprising a casing, a plurality of members having threaded shanks projecting through said casing, nuts screwed upon said threaded shanks and engaging said casing for adjustably holding said members, a plurality of insulators carried by said members and having apertures therethrough, and an infra-red element threaded through the apertures of said insulators.

2. A therapeutic lamp comprising a casing, a plurality of members having threaded shanks projecting through said casing, nuts screwed upon said threaded shank and engaging said casing for adjustably holding said members, a plurality of rigid, permanently formed insulators carried by said members and having apertures therethrough, and an infra-red element formed as a helix and threaded through the apertures of said insulators.

In testimony whereof, the signature of the inventor is affixed hereto.

WILLIAM TURNOR LEWIS.
